United States Patent Office

Des. 195,750
Patented July 23, 1963

195,750

FOUNTAIN PEN

Ernst Rösler, Hamburg, and Konrad Kressel, Hamburg,
Poppenbuttel, Germany, assignors to Montblanc-Simplo
G.m.b.H., Hamburg, Germany

Filed Feb. 20, 1961, Ser. No. 63,989

Claims priority, application Germany Dec. 13, 1958

Term of patent 14 years

(Cl. D74—17)

FIG. 1 is a side elevational view of a fountain pen embodying our new design.

FIG. 2 is a top plan view thereof.

FIG. 3 is a bottom plan view thereof.

FIG. 4 is a front elevational view thereof.

FIG. 5 is a front elevational view of the fountain pen shown in FIG. 1 after removal of the cap.

FIG. 6 is a side elevational view thereof.

FIG. 7 is a rear elevational view thereof.

FIG. 8 is a top plan view of the fountain pen shown in FIG. 1 after removal of the cap.

This application is a continuation-in-part of our application Ser. D. 55,256 filed March 30, 1959 and now abandoned.

We claim:

The ornamental design for a fountain pen, as shown and described.
